UNITED STATES PATENT OFFICE.

FRANK A. VALENTINE, OF APPONAUG, AND DAVID C. SCOTT, OF PROVIDENCE, RHODE ISLAND, ASSIGNEES TO HENRY L. SCOTT COMPANY, OF PROVIDENCE, RHODE ISLAND, A CORPORATION OF RHODE ISLAND.

TESTING MACHINE.

Application filed October 22, 1926. Serial No. 143,372.

This invention relates to improvements in testing machines employed for obtaining the strength or stretch of materials; and has for its object to provide mechanism of this character which is positive in its tension-applying movement and which movement will be automatically arrested upon reaching the end of its tensioning stroke and means being provided for quickly returning the pulling mechanism to its starting position after each testing operation.

A further object of the invention is the provision of a rack and a power driven pinion engaging the rack to apply tension strokes thereto, means being provided for arresting the power-applying mechanism at the end of its tension stroke and a gravity actuated means such as a weight or other suitable means being also provided for quickly returning the rack to its starting point after each tension stroke.

A still further object of the invention is the provision of a second rack operated by a weight for quickly returning the first rack to its starting position.

With these and other objects in view, the invention consists of certain novel features of construction, as will be more fully described, and particularly pointed out in the appended claims.

In the accompanying drawings:

Figure 1 is a plan view showing the gear casing partly in section and illustrating our improved mechanism.

Figure 2 is a front elevation showing the casing partly in section illustrating our improved mechanism.

Figure 3 is a side elevation partly in section showing a portion of the driving mechanism as operatively mounted on a cross shaft.

Figure 4 is a side elevation showing the two racks in connection with the gearing in the box.

Figure 5 is a group of mechanism illustrating the stop on the rack as engaging the shift mechanism to control the withdrawing action of the drive worm from engagement with its gear.

Figure 6 is a perspective view showing the rocker bracket in detail.

It is found in the practical operation of machines of this character for testing the strength or the stretch or both, of different

materials, of advantage to provide simple and effective mechanism whereby the pull may be positively and continuously applied to the work being tested and when the testing stroke or travel has been finished, to automatically trip the pulling mechanism which will return promptly and automatically to its starting position ready to repeat the operation; and the following is a detailed description of the present embodiment of our invention and showing one arrangement by which these advantageous results may be accomplished:—

With reference to the drawings, 10 designates the gear casing in which our improved mechanism is housed, power being applied to the mechanism through a pulley 11 preferably from an electric motor (not shown). From this pulley the power is transmitted through shaft 12 to the worm 13 inside the casing. This worm is arranged to mesh with the worm gear 14 which is mounted on a sleeve 15 to the inner end of which is connected a spur gear 16 and through which motion is imparted to the corresponding gear 17 on the shaft 18, which shaft is rotatably mounted in a forked rocker bracket 19, which bracket swings on the fixed shaft 20, the bracket being provided with an upwardly extending arm 21 having a roll 22 to engage a cam, presently described. In the space 23 of this rocker bracket and on the shaft 18 mounted in the bearings in this bracket is mounted a worm 24 to be swung by the bracket into and out of engagement with a worm gear 25, which latter gear is fixed on the shaft 26 and on this shaft is also fixed the spur gear 27. Meshing with this gear 27 is the pull rack 28 which is slidably guided in the upper and lower walls of the casing 10 the upper end of this rack being connected with the usual clamp 29 for gripping the lower end of the work 46 and on this rack is adjustably mounted the tripper dog 30 which is slid along the rack and secured in adjusted position by means of a screw 31. Also meshing with this rack 28 below gear 27 is a slightly larger gear 32 mounted on a short shaft 33 and a second vertically slidable rack 34 meshes with this gear 32 and is arranged to extend through the casing both above and below the same. On the lower end of this rack 34 is hung a weight 35 which serves to return the pull

90

100

105

rack to its starting position after the driving mechanism has been disconnected. A pawl 36 is mounted on the short shaft 37 and is provided with an operating arm 38, the lower end of which extends through the

5 shaft to engage a stop pin 39 to limit the back throw of the pawl when withdrawn from the teeth of the rack 34.

In order to automatically disconnect the 10 driving mechanism from the pull mechanism, we have provided a vertically-disposed push rod 40 which extends down into the box. On the upper end of this rod is a presser arm 41 extending out to be engaged by the dog 15 30 on the rack 28 when the latter has reached the end of its pulling stroke. On this push rod within the casing, we have mounted a cam 42, the working face of which is engaged by a roll 22 on the rocker 20 bracket arm 21, the lower end of this push rod being slidably mounted in bearing 40, and is slotted as at 43 to receive the guide pin 44 whereby the rod is prevented from rotating to hold its cam and its arm 41 in 25 proper operating alignment. The lower part of the casing is partitioned off to provide an oil well 45 containing a lubricant in which the gears dip to distribute lubrication to the operating mechanism.

30 On this push rod 40, we have also mounted a finger lever 46 by which the same may be lifted manually after having been pressed down by the dog on the pull rack, which upward movement of this rod serves to cause 35 the arm 21 to move outward on the cam 42 and swing the worm 24 back into engagement with the driving worm gear 25 to start another pulling action of the rack on the work 46. In other words, when it is desired 40 to start the pull rack 28 to exert a tension on the work, it is only necessary to lift the push rod 40 through the finger lever 46, the gears will then be in mesh to operate and draw downwardly the pull rack 28 until the 45 dog 30 contacts with the arm 41 on the push rod 40, when the bracket arm 21 under action of its spring 47 swings inward and serves to withdraw the worm 24 from the worm gear 25 which action releases the power from the 50 rest of the mechanism and permits the weight 35 to act through its rack 34 (which is lifted as rack 30 drops) and gear 32, upon this opposite rack 30 to return this pull rack quickly to its starting position.

55 If for any reason it is desired that this quick return should not be required the pawl 36 is tipped forward into engagement with the teeth of rack 34 which will prevent a return movement of the pull rack until the 60 pawl has again been withdrawn to permit the return action of the weight 35 and racks 30 and 34.

This improved driving mechanism for testing machines is very simple and practical in its construction, is effective in its

operation and by its use work may be quickly and accurately tested and after the test the mechanism automatically returns to its starting point ready to repeat the

70 operation.

The foregoing description is directed solely towards the construction illustrated, but we desire it to be understood that we reserve the privilege of resorting to all the mechanical changes to which the device is 75 susceptible, the invention being defined and limited only by the terms of the appended claims.

We claim:

1. In a testing machine, a pull member 80 through which tension is applied to the work being tested, driving mechanism for actuating said pull member in one direction, means for releasing said pull member from the action of said driving mechanism, and gravity actuated means for quickly returning said pull member to its starting position when so released.

2. In a testing machine, a pull rack 90 through which tension is applied to the work being tested, a power driven gear engaging said rack, means operable at the end of the driving stroke for rendering ineffective the driving action of said gear on said rack, and gravity actuated means for quickly returning said rack to its starting position.

3. In a testing machine, a pull rack 100 through which tension is applied to the work being tested, a gear through which said rack is driven, means operated at the end of each tension stroke for rendering ineffective the driving action of said gear, and a gravity actuated second rack arranged to act upon said power rack to return it to normal.

105 4. In a testing machine, a pull rack through which tension is applied to the work being tested, a gear through which said rack is driven, means operated at the end of each tension stroke for rendering ineffective the driving action of said gear, a second gear engaging said rack, a second rack engaging said second gear, and means acting upon said second rack to return the first rack to its starting point.

110 5. In a testing machine, a pull rack through which tension is applied to the work being tested, a gear through which said rack is driven, means operated at the end of each tension stroke for rendering ineffective the driving action of said gear, a second rack gear, and a gravity actuated rack arranged to act upon said second gear to return said pull rack.

115 6. In a testing machine, a pull rack 125 through which tension is applied to the work being tested, a power driven gear engaging said rack, means operable at the end of the driving stroke for rendering ineffective the driving action of said gear on said

rack, and adjustable means for preventing said return action when desired.

7. In a testing machine, a pull rack through which tension is applied to the work being tested, a gear through which said rack is driven, means operated at the end of each tension stroke for rendering ineffective the driving action of said gear, a second gear engaging said rack, a second

rack engaging said second gear, means acting upon said second rack to return the first rack to its starting point, and a stop member for preventing the return action of said mechanism when desired. ¹⁰

In testimony whereof we affix our signatures. ¹⁵
